Primary Examiner — Brett Miller*Assistant Examiner* — Jessica M Gebhart(74) *Attorney, Agent, or Firm* — IPRO, PLLC(57) **CLAIM**

The ornamental design for a pill box, as shown and described.

DESCRIPTION

FIG. 1 is a front and right side perspective view of an ornamental design for a pill box showing my new design; FIG. 2 is a rear and left side perspective view of the pill box; FIG. 3 is a front view of the pill box; FIG. 4 is a rear view of the pill box; FIG. 5 is a left side view of the pill box; FIG. 6 is a right side view of the pill box; FIG. 7 is a top view of the pill box; FIG. 8 is a bottom view of the pill box; and, FIG. 9 is a front and right side perspective view of the pill box in its open state.

The broken lines immediately adjacent the shaded areas represent the bounds of the claimed design while all other broken lines are directed to environment and are for illustrative purposes only; the broken lines form no part of the claimed design.

Any shading and cross-hatching are not features of the design but are utilized to illustrate the surface contours of the pill box in the drawings.
